US00D863305S

(12) **United States Design Patent** (10) **Patent No.:** **US D863,305 S**
(45) **Date of Patent:** **** Oct. 15, 2019**

(54) **SCANNER**

(71) Applicant: **BROTHER INDUSTRIES, LTD.**,
Nagoya-shi, Aichi-ken (JP)

(72) Inventor: **Keiichiro Egami**, Kuwana (JP)

(73) Assignee: **BROTHER INDUSTRIES, LTD.**,
Nagoya (JP)

(**) Term: **15 Years**

(21) Appl. No.: **29/586,173**

(22) Filed: **Dec. 1, 2016**

(30) **Foreign Application Priority Data**

Jun. 3, 2016 (JP) 2016-11907

(51) **LOC (12) Cl.** **14-02**

(52) **U.S. Cl.**

USPC **D14/422**

CLAIM

The ornamental design for a scanner, as shown and described.

DESCRIPTION

FIG. 1 is a perspective view of a scanner with the tray in a first, open position;

FIG. 2 is a front view thereof;

FIG. 3 is a top view thereof;

FIG. 4 is a right-side view thereof;

FIG. 5 is a left-side view thereof;

FIG. 6 is a rear view thereof;

FIG. 7 is a bottom view thereof; and,

FIG. 8 is a perspective view thereof with the tray in a second, closed position.

The broken lines depict unclaimed portions of the scanner and form no part of the claimed design.

1 Claim, 7 Drawing Sheets
